UNITED STATES PATENT OFFICE.

MARTIN PENNINGTON FERNEYHOUGH, OF STOKE-UPON-TRENT, ENGLAND.

CHARGING AND DRAWING OF POTTERS' OVENS.

1,234,648.

Specification of Letters Patent.

Patented July 24, 1917.

Application filed September 14, 1916. Serial No. 120,043.

To all whom it may concern:

Be it known that I, MARTIN PENNINGTON FERNEYHOUGH, a subject of the King of Great Britain and Ireland, residing at 77 5 Chaplin road, Normacot, Stoke-upon-Trent, England, have invented certain new and useful Improvements Relating to the Charging and Drawing of Potters' Ovens, of which the following is a specification.

10 In the manufacture of pottery the ware is placed, for the firing process, in saggars which are stacked in the ovens. The charging or placing of the saggars in the oven and the subsequent removal or drawing of 15 the same from the ovens is a long and laborious process.

My invention comprises for provision within the oven a portable and collapsible vertical gauntree fitted with lifting and 20 lowering devices or hoists, together with one or more adjustable horizontal arms or stages whereby the saggars can be conveyed between the hoist and any part of the oven interior.

25 In the accompanying sheets of explanatory drawings:—

Figures 1, 2 and 3 illustrate diagrammatically by front view, side view and plan respectively a charging and discharging apparatus constructed in accordance with this 30 invention.

In carrying the invention into effect as shown, the vertical gauntree comprises a frame or standard *a* made up of steel bars 35 of angle or other section, or it may be made from steel tubing. To permit of its being readily placed within or withdrawn from the oven, the gauntree is made up in any convenient manner of detachable parts 40 which can be readily connected or disconnected.

The raising and lowering of the saggars within the oven is effected by means of cages *b* which are operated by hand or power 45 driven lift mechanism of any convenient type. Preferably one pair of cages at least are employed with each gauntree and are arranged to balance, or so that the one ascends while the other descends. Preferably 50 the cages come to a common position at the bottom of the gauntree owing to the narrowness of the doorway through which the saggars pass into or out of the oven. To effect this the cage guides are suitably constructed 55 so that they come together at the lower ends.

For enabling the saggars to be withdrawn

from or put upon the gauntree cages at convenient heights or levels and to be placed at or drawn from all parts of the oven interior, transport arms or stages *c* are provided upon the gauntree. Each arm or stage is constructed as shown in sections which can telescope. Also the section adjacent to the gauntree is made to slide thereon. This section is constructed from two parts with 60 curved abutting ends as illustrated so that the main portion of the stage can be swung laterally relatively to the gauntree. Preferably vertical adjustment is effected by winch actuated ropes *d* from which the arms 65 are suspended. The outer ends of the arms are supported on standards *e* which are readily adjusted to any height or position in the oven. The ropes *d* are also attached to the standards. 70

When an oven is to be charged or to have the saggars placed therein, the gauntree is assembled or extended for service within the oven, being set up in a position preferably just within the doorway or admission aperture. As the saggars are placed by placers or operatives one upon another the stack or pile gradually rises up from the oven floor until it becomes out of convenient reach. The placer then ascends the gauntree 80 and takes up a position upon a platform adjacent to one of the arms or stages to which the saggars are raised by the gauntree. By passing from stage to stage the oven is thus charged, when the gauntree is 85 withdrawn. In like manner when the saggars are to be drawn from the oven the gauntree is again brought into service within the oven. 90

The invention is not limited to any particular manner of constructing the gauntree and arms and supports for the outer ends of the latter, or the different actuating mechanisms. The foregoing description and the drawings indicate the essential features and 95 details may be varied to meet requirements. 100

Having thus described my invention what I claim as new and desire to secure by Letters Patent is:—

1. Portable means for charging and drawing saggars into and out of potters' ovens, comprising a collapsible vertical gauntree, a hoist in said gauntree, and a horizontal arm attached to the gauntree and movable vertically thereon, substantially as described. 105

2. Portable means for charging and drawing saggars into and out of potters' ovens,

comprising a collapsible vertical gauntree, a hoist in said gauntree, and an extensible horizontal arm attached to the gauntree and movable vertically thereon, substantially as 5 described.

3. Portable means for charging and drawing saggars into and out of potters' ovens, comprising a collapsible vertical gauntree, a hoist in said gauntree, and a plurality of 10 horizontal arms attached to the gauntree and movable vertically thereon, substantially as described.

4. Portable means for charging and drawing saggars into and out of potters' ovens, 15 comprising a collapsible vertical gauntree, a hoist in said gauntree, a horizontal arm attached to the gauntree and movable vertically thereon, and a collapsible support for the outer end of the arm, substantially as 20 described.

5. Portable means for charging and drawing saggars into and out of potters' ovens, comprising a collapsible vertical gauntree, a hoist in said gauntree, a horizontal arm 25 attached to the gauntree and movable vertically thereon, a collapsible support for the outer end of the arm, and raising and lowering mechanism for the arm, substantially as described.

30 6. Portable means for charging and drawing saggars into and out of potters' ovens, comprising a collapsible vertical gauntree, a hoist in said gauntree, a horizontal arm attached to the gauntree, a collapsible support 35 for the outer end of the arm, and an adjustable suspensory device for the arm

attached to the gauntree and the support, substantially as described.

7. Portable means for charging and drawing saggars into and out of potters' ovens, 40 comprising a collapsible vertical gauntree, a pair of hoists in said gauntree, guides for the hoists uniting in a common position at the lower end of the gauntree, and a horizontal arm attached to the gauntree and 45 movable vertically thereon, substantially as described.

8. Portable means for charging and drawing saggars into and out of potters' ovens, 50 comprising a collapsible vertical gauntree, a hoist in said gauntree, a horizontal arm attached to the gauntree and movable vertically thereon, and means permitting a lateral swing of the arm relatively to the gauntree, substantially as described. 55

9. Portable means for charging and drawing saggars into and out of potters' ovens, comprising a collapsible vertical gauntree, a pair of hoists in said gauntree, guides for the hoists uniting in a common position at 60 the lower end of the gauntree, a plurality of vertically movable and telescopic horizontal arms attached to the gauntree, means permitting a lateral swinging of each arm relatively to the gauntree, collapsible supports for the outer ends of the arms, and adjustable arm suspending devices attached to the gauntree and supports, substantially as described. 65

In testimony whereof I have signed my 70 name to this specification.

MARTIN PENNINGTON FERNEYHOUGH.
